CLAMP BUCKLE

Louis A. Barrett, Lynn, Mass.

Application August 17, 1938, Serial No. 225,334

1 Claim. (Cl. 24—191)

The present invention pertains generally to buckles, more particularly to friction grip buckles, and specifically to friction grip buckles of the locking lever type, especially adapted for the interconnecting of the ends of waist belts, straps of shoes and of sportswear and the like, and for a variety of analogous purposes, without necessitating the puncturing of the belt, strap or the like at various points, as would have to be done 10 were the conventional type of tongued buckle employed: such a friction grip buckle may aptly be termed a clamp buckle.

As is well known to those skilled in the art, friction grip buckles of this type, for successful use, are generally limited to belts of uniform and specified thicknesses, i. e., a given clamp buckle is most successfully usable with a strap of a specific thickness; and a strap, substantially greater or less in thickness than the strap of the specific thickness, is not usable with the given clamp buckle. This limitation upon the use of clamp buckles is due to the fact that they are ordinarily constructed to accommodate a specific thickness of material, and any substantial deviation 25 in thickness from the selected specific thickness of material either permits the material to slip within the clamp buckle, or renders impossible the insertion and the engagement of the material in the clamp buckle.

30 The primary object of my invention is to provide an improved clamp buckle of the locking lever type which will accommodate, and adapt itself for use with, materials of substantially differing thickness.

35 Another object of my invention is to provide an improved clamp buckle of the character described which is remarkably simple in construction and inexpensive to manufacture.

The attainment of these and other objects of 40 my invention and the advantages attendant upon its use will become apparent, especially to those skilled in the art, from a consideration of the following description, together with the accompanying drawing, which forms a part of the specification, wherein:

Figs. 1, 2 and 3 represent an underside plan view, a side elevation, and an end view, respectively, of the plate or shell of the improved clamp buckle.

50 Figs. 4, 5 and 6 represent an underside plan view, a side elevation, and an end view, respectively, of the locking lever of the improved clamp buckle.

Fig. 7 is an underside view of the assembled 55 improved clamp buckle, with one end of a strap

connected to the locking lever, and a portion of a strap engaged between the plate and the locking lever of the improved clamp buckle.

Fig. 8 is a side elevation in section along the line 8, 8 of Fig. 7, showing the engagement of a portion of a strap between the plate and the locking lever of the improved clamp buckle. 5

Fig. 9 is an end view, seen from the right, of the assembled improved clamp buckle shown in Figs. 7 and 8. 10

Fig. 10 is another end view, seen from the right, of the assembled improved clamp buckle shown in Figs. 7 and 8, but in this view, the portion of a strap engaged between the plate and the locking lever of the improved clamp buckle is substantially thicker than the corresponding portion 15 of a strap shown in Figs. 8 and 9.

Figs. 11 and 12 represent an underside plan view and an end view, respectively, of a modification of the locking lever of the improved clamp 20 buckle.

Fig. 13 is an end view of an assembled improved clamp buckle, provided with the locking lever shown in Figs. 11 and 12, showing the engagement of a portion of a strap of oversize 25 thickness between the plate and the locking lever of this modification of the improved clamp buckle.

In the drawing, 1 is the plate or shell of the improved clamp buckle, having inner and outer 30 faces curved in the manners shown, and having the sides 2 mutually parallel and substantially perpendicular to the plane of the plate 1. Extensions of portions of the sides 2 from the lugs 3, which are provided with the holes 4 for the reception of the pivot pins of the locking lever. The locking lever 5, in thickness somewhat less than the thickness of the plate 1, comprises an end portion 6, provided with a slot 7 to receive a strap 8, which either may be looped and fastened 35 to itself in the manner shown in Fig. 8, or may be fastened to the locking lever 5 by eyelets passing through the strap and the holes 9 in the middle portion of the locking lever, a middle portion 10, provided with the holes 9 and the pivot pins 11, receivable in the holes 4 in the lugs 3 of the plate 1, and a locking portion 12, angularly disposed to the middle portion 10 and provided with a slot 13 extending into the middle portion 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870

locking portion 12 into two friction members 14, 14. Particular attention should be given to the curvatures of the outer edges of the two friction members 14, 14 of the locking portion 12 of the locking lever 5, inasmuch as they are greater 55

- than is the curvature of the inner face of the plate 1 in the intersection of the plane of the friction members 14, 14 with the inner face of the plate 1, so that the distance between the inner face of the plate 1 and the outer edges of the friction members 14, 14 at the point 15 is slightly less than is the distance between the inner face of the plate 1 and the outer edges of the friction members 14, 14 at the points 16, 16.
- 5 10 When now a strap 17, in thickness slightly greater than the distance between the inner face of the plate 1 and the outer edges of the friction members 14, 14 at the point 15, is inserted into the opened improved clamp buckle, and the locking lever 5 is manipulated to close the improved clamp buckle, the strap 17 becomes engaged between the inner face of the plate 1 and the outer edges of the friction members 14, 14, with stress exerted upon the strap 17, in amount somewhat 15 greater near the center of its width than at its edges. Such engagement is shown in Fig. 9. If now this strap 17 is removed from the improved clamp buckle, and a strap 18, in thickness somewhat greater than the strap 17, is inserted into the opened improved clamp buckle, and the locking lever 5 is manipulated to close the improved clamp buckle, the greater thickness, or rather the too-great thickness, of the strap 18 causes the middle portion 19 of the locking lever 5 to 20 yield slightly and to become bent outwardly to a very slight extent, as is shown in Fig. 10 at 19; and the bend in the middle portion 19 of the locking lever 5 manifests itself by the development of a line of bending starting at the end of the slot 25 13 and extending longitudinally with respect to the improved clamp buckle. The strap 18 is now engaged between the inner face of the plate 1 and the outer edges of the friction members 14, 14, with stress exerted upon the strap 18, in amount substantially 30 uniformly distributed along the outer edges of the friction members 14, 14. The range of thicknesses of straps accommodatable by the improved clamp buckle is substantially proportional to the difference in the distances between the inner face of the plate 1 and the outer edges of the friction members 14, 14 at the points 15 and 16, 16, respectively.
- 35 40 45 50 55 60

This adaptability of the improved clamp buckle to the thickness of the strap inserted therein, attained by the slight deformation of the middle portion 19 and minute rotational displacements of the friction members 14, 14, of the locking lever 5, is made possible by the presence of the slot 13; and it will be noted in Figs. 9 and 10 that the deformation of the middle portion 19 of the locking lever 5 effects a transformation of the shape of that portion of the slot 13 in the locking portion 12 of the locking lever 5 from a rectangle to a trapezium, with the shorter parallel side defined by the engaged strap 18. The width of the slot 13 in the locking portion 12 of the locking lever 5 and the length of its extension into the middle portion 19 of the locking lever 5 are de-

termined by the range of thicknesses of straps to be accommodated by the improved clamp buckle and by the character of the material out of which the improved clamp buckle is constructed, but these details of construction will present no difficulties to those skilled in the art.

The realization of the objects and purposes of my invention can be attained in the use of straps of an even greater range of thicknesses by means of a modification in the locking portion of the locking lever of the improved clamp buckle, as is shown in Figs. 11 and 12. In this modification of my invention, two slots 20, 20, extending into the middle portion 21 of the locking lever, divide the locking portion of the locking lever into three friction members, of which the middle friction member 22 is only indirectly subjected to stresses exerted on the pivot pins of the locking lever. If desired, this middle friction member 22 may be accorded a length extending slightly beyond the curve defined by the outer edges of the two outer friction members 23, 23, either by so forming it initially, or by bending inwardly toward the plate of the improved clamp buckle the middle portion 21 of the locking lever with which the middle friction member 22 is integral. When a strap of oversize thickness is inserted into the improved clamp buckle provided with such a locking lever, that part of the middle portion 21 of the locking lever, with which the middle friction member 22 is integral, will become bent outwardly along a line extending transversely with respect to the improved clamp buckle, and, at the same time, the middle portion 21 of the locking lever will yield slightly and will become bent outwardly to slight extents along lines extending longitudinally with respect to the improved clamp buckle and starting at the ends of the slots 20, 20, with the result that the shapes of those portions of the slots 20, 20 in the locking portion of the locking lever are transformed from trapeziums to trapezoids, as shown in Fig. 13.

Although the improved clamp buckles herein described and illustrated embody the preferred forms of my invention, yet my invention is susceptible of such further modifications as may be fairly comprised by the scope of the appended claim.

Having thus described my invention, I claim:

A clamp buckle comprising a plate provided with lugs adapted to receive the pivot pins of a locking lever and a locking lever having a middle portion provided with pivot pins, a locking portion angularly disposed to the middle portion, and a slot bifurcating the locking portion and extending into the middle portion of the locking lever, the transverse outer edges of the locking portion of the locking lever having curvatures greater than the curvature of the inner face of the plate in the intersection of the plane of the locking portion of the locking lever with the inner face of the plate.
